UNITED STATES PATENT OFFICE.

GEORGE E. CHATILLON, OF NEW YORK, N. Y.

TWINE-HOLDER.

1,005,155.

Specification of Letters Patent. Patented Oct. 10, 1911.

Application filed July 2, 1909. Serial No. 505,603.

To all whom it may concern:

Be it known that I, GEORGE E. CHATILLON, a citizen of the United States, and a resident of the city, county, and State of 5 New York, have invented certain Improvements in Twine-Holders, of which the following is a specification.

This invention relates to certain improvements in holders such as are particularly 10 designed and adapted for use in stores and shops for holding ball twine and the like, and the object of the invention is to provide 15 a device of this character of a simple and comparatively inexpensive nature, formed 20 from sheet metal in a novel and improved way, whereby material advantages and economy are attained in manufacture, and the device is rendered lighter and stronger than other similar holders such as have been here- 25 tofore formed from cast metal.

The invention consists in certain novel 30 features of the construction and combinations and arrangements of the several parts of the improved twine holder, whereby cer- 35 tain important advantages are attained, and the device is rendered simpler, less expensive and stronger, and otherwise better adapted and more convenient for use all as will be 40 hereinafter fully set forth.

The novel features of the invention will 45 be carefully defined in the claim.

In order that my invention may be the 50 better understood I will now proceed to de- 55 scribe the same with reference to the accom- 60 panying drawings, wherein—

Figure 1 is a side elevation, drawn upon 65 a small scale, showing a twine holder con- 70 structed according to my invention; Fig. 2 75 is an axial section taken vertically through 80 the device; Fig. 3 is a fragmentary sec- 85 tional view taken through the meeting edges 90 of the members of the device; Fig. 4 is a 95 view showing a blank adapted for use in 100 forming one of the members; Fig. 5 is a 105 view of a blank suitable for the formation 110 of the other member, and Fig. 6 is a frag- 115 mentary sectional view showing a modified 120 form of the device which will be hereinafter 125 referred to.

As shown in these views the improved 130 twine holder comprises two similar hemi- 135 spherical members 1 and 2, adapted to be 140 fitted together as shown in Figs. 1 and 2 to 145 produce a rounded or spherical casing of a

diameter adapted to receive within it a ball 55 of twine or the like to be held.

According to my invention, the members 1 and 2 are formed from sheet metal, such as 60 steel, for example, of sufficient gage, and are produced from similar circular or rounded 65 flat blanks, such as are shown in detail in Figs. 3 and 4 of the drawings, the blank 3 shown in Fig. 4, serving for the formation of the member 1 while the blank 4, shown in Fig. 4, serves for the formation of the mem- 70 ber 2.

Each of the blanks 3 and 4 as herein 75 shown, is provided with a small central aperture 5, and also with an annular series 80 of larger apertures 6, 6, concentric around 85 said central aperture 5, and spaced there- 90 from by an annular imperforate portion 7, and said annular series of apertures 6, 6 95 are also concentric with the perimeter of the 100 circular or rounded blank, and are spaced 105 therefrom by an annular imperforate por- 110 tion 8. The apertures 6, 6 are also spaced 115 apart from each other, as herein shown, by 120 portions 9, 9 of the blank extended between 125 them, and which afford integral connections 130 between the imperforate inner and outer 135 annular parts 7 and 8.

In producing one of the cup-like hemi- 140 spherical members from such a blank, the 145 flattened blank is formed up by means of 150 dies or otherwise to impart such cup-like or 155 hemi-spherical formation thereto, whereby 160 the inner imperforate portion 7 is caused 165 to form the bottom or top of the cup-like 170 member, while the apertured portion sur- 175 rounding said inner imperforate portion is 180 pressed upwardly from said inner portion or 185 bottom, to afford the rounded side walls of 190 the member, the imperforate peripheral por- 195 tion 8 rising above such apertured portion 200 and affording a rim continuously extended 205 around the peripheral edge of the cup-like 210 member and adapted for accurate contact 215 upon the similar rim produced at the meet- 220 ing edge of the other member, as clearly 225 shown at 10 in Figs. 1, 2 and 3.

The forming up of the cup-like members 230 1 and 2 from the flattened blanks, as above 235 described, is materially facilitated by the 240 employment of the apertures 6, 6 which 245 weaken that portion of the blank which lies 250 between the portions 7 and 8, the connecting 255 portions 9, 9 extended between said aper- 260

tures 6, 6 being adapted to be elongated during the forming or drawing up of the outer portions of the blank, so as to facilitate the operation of the dies or other tools, and to permit the members to be produced from blanks of comparatively small diameter and thin gage. During the formation of said members from the blanks as above described, the apertures 6, 6 become elongated as seen at 11 in Figs. 1 and 2, by reason of the stretching of the connecting parts 9, 9. Said apertures, where present, serve to materially lighten the structure, and also to afford a desirable ornamentation to the improved twine holder, for which reason they may be made of any desired shapes.

As herein shown one of the cup-like members, as 1, is provided around the margin of its perimetral portion 8, with an outwardly swaged part 12, affording an inclosed shouldered portion within which the edge portion of the other member is adapted to be accurately received, as shown in Figs. 1, 2 and 3, in order to afford a secure and substantial joint between the members when in closed adjustment, despite the comparative thinness of the material from which they are produced, and at one side of one of the said members, adjacent to said outwardly swaged part 12 of member 1, as herein shown, is produced a narrow opening or slot 14, wherein is adapted to be received a bent tongue or extension 15, integrally produced upon and projecting from the rim or margin of the other member, as 2, this construction affording an inexpensive and secure hinge connection between the members, whereby they are adapted to be opened for the insertion of the twine, and closed together to properly house the same. At its side opposite to the hinge extension or tongue 15 I have also shown the member 2 provided with a similar projecting integral tongue or extension 16, which is adapted to be bent as shown at 17 in Fig. 2 to produce a shoulder adapted to be extended outside the outwardly swaged rim 12 of the member 1, and to be engaged beneath the same at a point opposite the hinge connection between the members, thereby affording an extremely simple and inexpensive spring catch for holding the members in closed adjustment, but capable of being readily disengaged from said outwardly swaged part of member 1 when it is desired to separate the members for the insertion of the twine.

As herein shown, the members 1 and 2 are similar to each other except with regard to those portions which are modified as above described at their meeting edges to afford effective connection of the thin sheet metal members, so that either one of said members may be uppermost when the parts are assembled for use, and when the twine

holder embodying my improvements is intended to be rested upon a counter, as shown in Figs. 1 and 2, I provide the same with a base member 18, which may be produced from cast metal, if desired, or may be otherwise given a weight suitable to permit of supporting the device in upright position and to prevent it from being too readily overturned. As shown in Fig. 2, such base member 18 is secured to the sheet metal body of the improved holder by means of a shank or reduced part 19 passed through the central opening 5 of the lowermost member 1, and headed at the inner surface of the same. Where this construction is employed, the central aperture 5 of the upper cup-like member 2, if present, will serve for the passage of the free end of the twine, so that the same may be readily drawn out from the improved holder.

Where the improved twine holder is to be suspended above a counter or the like, as is also customary in devices of this character, the central aperture of one member, as the member 2, shown in Fig. 6, may serve for the passage of the shank or a swivel or eye 20, by means of which the holder may be suspended from a hook or other overhead support, in order that the free end of the twine shall depend over the counter or table whereat the twine is to be used.

From the above description of my improvements, it will be seen that the improved twine holder made according to my invention is of an extremely simple and comparatively inexpensive nature, and is particularly well adapted for use by reason of its simplicity and cheapness and of the strength and durability afforded by the employment of the cup-like sheet metal members which permits the device to be made from comparatively thin and light material without liability of breakage from rough usage, and it will also be obvious from the above description that the device is susceptible of some modification, within the scope of the appended claim, without material departure from the principles and spirit of the invention, and for this reason I do not desire to be understood as limiting myself to the precise formation and arrangement of the several parts herein set forth in carrying out my invention in practice.

Having thus described my invention, what I claim and desire to secure by Letters Patent is—

A twine holder comprising two semi-spherical sections in a hinged relation when assembled, each section being formed from a blank of sheet metal having its perimetral portion provided with elongated radially disposed perforations affording a weakened portion to permit the blank being bent into semi-spherical form, one of said blanks

having its edge portion bent outwardly to form a shoulder and having a perforation adjacent said shoulder, the second blank having oppositely disposed integral tongues, 5 one of said tongues to pass through the last named perforation and surround the edge portion of the first named blank to effect a hinge, the second tongue affording a spring retaining clip and bent to produce a shoulder 10 to contact with the under surface of the shoulder of the first named blank, the said

blank having perimetral slots therein in alignment with the edges of the second tongue.

In witness whereof I have hereunto 15 signed my name, in the presence of two subscribing witnesses.

GEORGE E. CHATILLON.
